UNITED STATES PATENT OFFICE

2,638,951

COLLAPSIBLE TANK AND STABILIZER
MEANSFranklin E. Smith, South Dartmouth, and
Nathan H. Friedman, North Dighton, Mass.

Application December 18, 1950, Serial No. 261,412

1 Claim. (Cl. 150—0.5)

1

This invention relates to an improved collapsible tank structure of the type described in an earlier Patent No. 2,507,939, issued May 16, 1950, in which a plurality of wall members of water-resistant fabric material are secured together by stitching to form a portable container useful in conveying water in connection with fire fighting operations and similar purposes.

In the course of transporting the filled tank either by hand or in vehicles employed for similar purposes, it is found that lateral displacement of fluid held in the tank may raise problems making the handling of the filled tanks more difficult than would otherwise be the case. The present invention is concerned with the problem indicated and seeks to provide an improved collapsible tank structure in which there is included means for resisting or retarding change in position of fluid bodies contained in the tank. It is further an object of the invention to devise a simple and efficient stabilizing means which can be incorporated directly in the tank structure as an integral part of it and to so arrange and support the stabilizer means that it does not interfere with the utility of the tank member as a collapsible container body.

These and other objects and novel features will be more fully understood and appreciated from the following description of a preferred embodiment of the invention selected for purposes of illustration and shown in the accompanying drawings, in which

Fig. 1 is a plan cross-sectional view of the stabilizer equipped tank of the invention, the section being taken on the line 1—1 of Fig. 2 to particularly illustrate the handles or carrying straps for the tank structure;

Fig. 2 is a vertical cross-section taken approximately along the line 2—2 of Fig. 1, with parts of the corner seam sections left out to indicate generally the two stabilizer elements and with the tank side walls further indicated in section in order to more clearly indicate the points of joinder of the edges of the stabilizer elements with the tank fabric along the corner seams;

Fig. 3 is another plan cross-section taken approximately on the line 3—3 of Fig. 2 to further indicate the diagonal arrangement of the stabilizer elements illustrated in Fig. 2;

Fig. 4 is a detail elevational view of one of the stabilizer members removed from the tank.

In the structure shown in the drawings, numerals 10, 12, 14, and 16 denote four side wall portions preferably comprised of a fabric material, such as canvas or the like, and which has

been waterproofed in the manner well known to the art to provide a water-resistant character of the necessary degree. These side wall portions are secured together at their adjacent edges to form seams 18 which, in an erect position of the tank, extend diagonally upward, as will be apparent from an inspection of Fig. 3. Top and bottom sections 20 and 22 close the openings at the upper and lower sides of the tank structure and the lower ends of the side portions are secured thereto by stitching to provide flat bottom seams 24. Communicating with the interior of the tank structure through the top section 20 is a tubular member 26 through which fluids may be led into the tank and removed, as desired. Numerals 28 and 30 denote handles or straps utilized in lifting the tank when in a filled state.

In accordance with the invention the interior 20 of the tank structure is provided with two novel stabilizer means secured between opposed seams 18 in spaced-apart relation, one above the other. In a preferred form the stabilizers comprise flexible sheet elements which extend or hang downwardly of the tank when the latter member is filled with a fluid body to oppose and resist changes in position and especially lateral displacement of the fluid during such times as the filled tank is in transit.

Thus, numeral 32 indicates one such sheet element in an uppermost position which element may conveniently be formed of the same fabric material as the side wall portions of the tank. As will be observed, the stabilizer 32 is secured 35 along its two opposite side edges to opposed portions of the side walls and preferably this is achieved by cutting the stabilizer 32 in the form shown in Fig. 4 so as to provide parallel top and bottom edges 32a and 32b and angularly extending side edges 32c and 32d, the latter being of a shape chosen to coincide with the angularity of the seams 18 so that these side edges 32c and 32d may be stitched directly into the seams 18.

With a stabilizer construction as above described it is pointed out that the same outwardly directed force which acts to keep the side walls held apart from one another when the tank is filled with fluid also act to maintain the stabilizer in a substantially rigidly stretched position. When thus rigidly extended the stabilizer can and does offer a material resistance to inertial forces seeking to create a lateral displacement of the fluid as a result of the tank being moved about.

It will be seen that with a single stabilizer

element, such as the member 32, greatest resistance to sway forces will be realized with respect to those force components which are acting substantially at right angles to the vertical plane in which the stabilizer 32 lies. In order to deal equally as well with force components acting in a direction parallel with the stabilizer 32, or substantially so, there may be provided a second sheet member 34 which is disposed below element 32 to extend in a vertical plane running at right angles to the plane of said sheet member 32 and which may conveniently be secured in the manner already described between seams 18 which furnish the desired arrangement, as suggested in Fig. 2. Similarly, other stabilizer elements may be provided at any desired angle of intersection with one another to provide a greater or lesser amount of resistance, as desired.

It will be seen that the stabilizer means of the invention, therefore, serves a highly useful purpose in increasing the efficiency of portable or collapsible type fabric tanks, and the difficulties heretofore experienced in handling such containers in a filled state is greatly reduced.

While we have shown preferred embodiments of the invention, it will be understood that some change and modification may be practiced within the limits of the claims appended hereto.

We claim:

An improved collapsible tank structure comprising four side wall portions which correspond in shape to the sides of a truncated pyramid, adjacent edges of said side wall portions being secured, one to another, to form seams which provide four separated corners for the tank struc-

ture, top and bottom tank sections secured to the side wall portions, said side wall portions, when containing a fluid body, being adapted to occur in an inclined position, a fluid conduit member located in the said top section, a stabilizer sheet located at the top part of the tank structure, two opposite edges of said stabilizer sheet being secured internally of the tank structure along two opposite corners thereof in a position to resist laterally directed inertial forces of a fluid in the tank acting in one direction, and a second stabilizer sheet located cross-wise below the said first stabilizer sheet at the bottom part of the tank structure, two opposite edges of the said second sheet being secured internally along two opposite remaining corners of the tank structure in a position to cooperate with the first stabilizer sheet and resist laterally directed inertial forces of the fluid in the tank acting substantially at right angles to the plane of the said first sheet material.

FRANKLIN E. SMITH.
NATHAN H. FRIEDMAN.
